OSCILLATORY MAGNETIC MOTOR

John Nelson Frey, Union, N. J., assignor to The
United States Printing & Lithograph Com-
pany, New York, N. Y., a corporation of Ohio

Application September 21, 1935, Serial No. 41,622

5 Claims. (Cl. 40—51)

This invention relates to improvements in oscillatory magnetic motors and has more particular relation to improvements in motors designed for use in connection with movable displays for advertising purposes.

The invention consists of a motor designed for continuous movement to operate some movable part of an advertising display by a very low voltage current, such for instance, as may be supplied by dry cells or storage battery of very low voltage to avoid all fire hazards.

The invention consists in a motor so designed and mounted that it may be instantly attached or removed from the display panel of an advertising device; said panels being constructed to be placed in display windows in an approximately upright position.

The invention is an improvement on the pending application of John G. Ruckelshaus, No. 30,952 filed July 12, 1935.

In devices of the present type, the oscillating motor on the back of the display communicates an oscillating movement to some part moving over the face or front of the display. The invention, therefore, consists of means for securing or detaching the motor to the back of the display in such a manner that it may be instantly removed from the display notwithstanding the connections are projecting through narrow slots of the display.

In the accompanying drawings, forming part of this specification,

Figure 1 represents one of the aforesaid motors with the improved attaching means, the display being broken away and the movable display element being shown in dotted lines.

Figure 2 represents an end elevation of the same.

Figure 3 represents the cardboard attaching block for securing the motor to the back of the display.

Figure 4 represents a horizontal section through the same.

Figure 5 represents a modified form of attaching block for the motor constructed of metal.

Figure 6 represents a section through the same on the line 6—6 of Figure 5.

Figure 7 represents the attaching block that is detachably secured to the motor and supports the movable display.

Figure 8 represents a horizontal section through the same.

Figure 9 represents a detail side elevation of the electric switch just after it has made contact, and

Figure 10 represents a similar view with the switch being reset to contact position.

Described in general terms, the motor which is shown in the aforesaid pending application comprises a yoke 2 to which is attached a curved soft iron bar 3. This bar is preferably spot welded to the bottom of the yoke. The upper end of the yoke 2 supports a trunnion 4 on which is rigidly mounted the main oscillating bar 5 of the motor.

The lower end of the bar 5 supports a bobbin 10 or solenoid coil 6. This coil as best shown in Figure 2 has one end of its winding 7 grounded on the frame while the companion wire 8 of the coil is connected to the contact 14 of the switch which is mounted in a rigid arm 10 secured to the yoke, 15 by suitable insulated mountings. The coil 6 as it swings back and forth like a pendulum is so arranged that it swings over the iron bar 3 and the solenoid is given a momentary impulse and then released to cause the bar 5 to continue an oscillating movement.

The lower end of this bar is provided with a counter-balancing arm 11 having a counter weight 12. The purpose of this latter bar and arm is to form, together with the coil, a counter-weight to counter-poise the weight of the arm 13 which is to travel over the face of the display and which is mounted upon the upper end of the bar 5. The switch is so arranged that the contact pin 9 contacts the arm 14 upon the forward swing of the bar. As the pin 9 continues its forward movement it moves the pivoted switch plate 15 so that the pin will not contact the contact 14 on the back swing of the bar. This back swing, however, again moves the switch plate 15 to bring the contact 14 into the path of the pin 9 for the succeeding operation, this latter condition being shown in Figure 10.

In displays of the present type which are placed in the hands of users in great numbers, a large percentage of the cost of producing such displays is the motor mechanism. For this reason, it is very desirable that such motor mechanism be so arranged that it may be attached to different displays having lithographed front panels illustrating different moving parts of different motivated pictures. For this reason, the motor, instead of being permanently attached to the back of the display, is simply slid into place in the following manner. One arm of the yoke 2 is provided with a pendent segmental plate 16, the segment of this plate being struck on an arc which is centered on the trunnion 4. The cardboard block 17 for supporting the arm 16 and the yoke 2 is glued or otherwise secured to the back 50 55 45 40 50 55

of the display 1 in such position that when the parts are in place as shown in Figure 1, the arm 6 may be disengaged from the segmental socket 18 by rotating the yoke 2 on the trunnion 4 without moving the oscillatory bar 5. The block 17 is made up of two thicknesses of cardboard 19 and 20. The slot 18 formed in the part 19 is closed on one side by the solid portion of the underlying part 20 so as to form a segmental slot 10 for the reception of the arm 16, the opposite side of the slot 18 being formed by the back of the display against which the part 19 is glued. A slot 21 is formed in the part 20 so that the upper end of the arm 16 will project into the same to 15 assist in firmly anchoring the yoke 2 in position; one arm of the lower edge of the yoke resting upon the upper edge 22 of the part 19. The part 20 is also provided with a flexible locking tongue 23 which snaps over the yoke 2 after the parts are 20 in position to prevent the yoke from rising from its seat at any time during the oscillation of the motor. If it is desired at any time to remove the motor, the tongue 23 is bent back to release the bottom of the yoke so that it may be moved upward on the pivot 4 and allow the segment 16 to 25 be drawn out of the slot 18. After this movement has taken place and after the movable part of the display on the upper end of the bar 5 has been removed, this latter bar may be slightly 30 tipped and the whole motor removed from the display by withdrawing the bar 5 through a slot 24 formed in the display. The portion of the display 13, which in the present instance is the representation of an arm with a hand, is attached to 35 the upper and outwardly bent end 25 of the bar 5 by means of the cardboard block 26 shown in Figure 7. This block is also made of two thicknesses of cardboard with a slot 27 in the uppermost. This block 26 is suitably glued to the upper end of the arm 13 thereby forming the socket 21 which receives the end of the bar 5.

It will be seen from the above that the arm 13 can be instantly removed by being forced upward. This operation leaves the bar 5 free to 45 be withdrawn through the slot 27.

It will be seen from the above that if the user of motivated displays has several such displays, he may move the motor from one display to another without any more effort than moving the parts from the slots shown in the blocks illustrated in Figures 3 and 7. In other words no mechanical adjustments or detachments are necessary and the motor parts are simply slipped out and into slots in making the transfer.

It has also been found that any vibration set up in the moving part of the motor and communicated to the yoke 2 will be best resisted by the segmental form of the arm 16 in its slot 18. This structure forms a lock against the outward movement of the yoke in addition to the lock afforded by the tongue 23.

It has been found desirable in very large displays in which the size and weight of the motor

must be increased to provide metallic attaching devices for the motor. These are best shown in Figure 5 in which a single plate 28 is stamped with a segmental channel 29 and an offset plate 30 having a notch 31 corresponding to the notch 5 21. A flexible tongue 32 is also formed on this metal plate corresponding to the tongue 23. The plate 33 by being offset from the plate 28 forms a shoulder 34 corresponding to the shoulder 22 and for like purpose. The plate 28 in this instance is formed with apertures 35 through which bolts or screws are passed to secure the plate to the back of the display.

I claim:

1. The combination with an advertising display, of an oscillatory motor having a supporting member and a pivoted actuator on said member, a movable display member, means connecting the latter member to the actuator, and detachable holding means between the supporting member and the display movable upon an arc with the actuator pivot as a centre.

2. The combination with an advertising display, of an oscillatory motor, having a supporting member and a pendulum actuator pivoted on 25 said member, a movable display member on the front of the display, means connecting the actuator and display member and passing through the display, and detachable holding means between the supporting member and the display capable 30 of detachment without moving the pendulum actuator.

3. The combination with an advertising display, of an oscillatory motor arranged to be detachably secured to the back of the display and 35 comprising a supporting member, a pendulum acting actuator pivotally supported on said member, an arc-shaped attaching arm struck on an arc whose centre is the actuator pivot, an attaching block secured to the back of the display 40 and having a slot to receive the arc-shaped arm of the supporting member, a movable device for the front of the display and means connecting said device to the pendulum actuator.

4. The combination with an advertising display, of an oscillatory motor having a supporting member and a pivoted actuator on said member, a movable display member, means connecting the latter member to the actuator, a segmental arm mounted on the supporting member, a block having 50 a segmental slot to receive the arm and mounted on the display and locking means for securing the arm within the slot against accidental displacement.

5. The combination with an advertising display, of an oscillatory motor having a supporting member and a pivoted actuator on said member, a movable display member, detachable means connecting the latter member to the actuator and detachable holding means between the supporting 60 member and the display.

JOHN NELSON FREY.
